UNITED STATES PATENT OFFICE.

LAWRENCE W. CARGILL, OF COLUMBUS, OHIO.

FEED MECHANISM FOR CONCRETE-MIXERS.

No. 926,172.

Specification of Letters Patent.

Patented June 29, 1909.

Application filed October 14, 1908. Serial No. 457,612.

To all whom it may concern:

Be it known that I, LAWRENCE W. CARGILL, a citizen of the United States, residing at Columbus, in the county of Franklin and 5 State of Ohio, have invented certain new and useful Improvements in Feed Mechanism for Concrete-Mixers, of which the following is a specification.

My invention relates to the improvement 10 of feed mechanism for concrete mixers and the objects of my invention are to provide simple and improved means for elevating concrete from a comparatively low point to a concrete mixer hopper, and to accomplish 15 this object by the employment of certain novel details of construction which will be more fully pointed out hereinafter. These objects I accomplish in the manner illustrated in the accompanying drawing, in 20 which:

Figure 1 is a front elevation of my improved mechanism, showing for the sake of clearness in illustration, a portion of the outer side flange of the elevating and carrying device removed, Fig. 2 is a plan view of the 25 same illustrating the position of my improved device with relation to an ordinary mixing machine, Fig. 3 is a side elevation of my device showing the same in conjunction 30 with a concrete mixer, Fig. 4 is a transverse section of the elevating device taken on line $x-x$ of Fig. 1, Fig. 5 is a detail view in perspective of a load leveling device which I employ, and, Fig. 6 is a detail view in perspective 35 of one of the conveyer blades or gates.

Similar numerals refer to similar parts throughout the several views.

In carrying out my invention, I employ a suitable framework which comprises parallel 40 horizontal beams 1 and 2, from which rise pairs of front and rear frame standards 3 and 4. 5 represents the elevator body which, as shown in the drawing, is in the form of a channeled ring or circular conveyer. As 45 shown in the drawing, the inner vertical side wall 5^a of the conveyer or elevator, is of greater thickness than the outer side wall which is shown at 5^b. The circular elevator body thus formed, has secured to the outer 50 side of its rear wall, a toothed ring or band 6, the external teeth of which are preferably in the nature of sprocket teeth, said toothed ring thus forming a permanent sprocket wheel attachment for the rear side of the elevator. 55 As shown in the drawing, the circular elevator is mounted to bear upon and against

four pairs of rollers 7, each pair of rollers being mounted to rotate upon a forwardly projecting fixed shaft or rod 8. As shown in the drawing, the upper rods 8 are supported by 60 suitable clamps or brackets 3^b in connection with the upper end portions of the frame standards 3, while the lower rods or shafts are similarly supported from the undersides of the frame beams 1. The rollers of each pair 65 are separated and each of said rollers is provided on its outer side with a flanged enlargement 7^a, said flanges embracing respectively the outer portions of the front and rear sides of the circular elevator body, while 70 the bodies of the rollers contact with the periphery of said elevator body.

Within the central portion of the channel of the elevator body, I provide a fixed rod 9 which curves to conform to the curvature of 75 said body, said rod extending from the center of the height of the elevator on one side to a point above the center of the height on the other. This rod is held in the position shown and described, by means of suitable 80 brace arms 10 which are rigidly connected with a frame cross piece 11, which connects the front standards 3. At desirable intervals, I provide the inner surface of the channeled elevator, with fixed brackets 12 and to 85 each of these brackets is hinged as indicated at 12^a the outer and shorter arm of an angular conveying or elevating gate or blade 13, the longer member of said blade inclining, as shown, in the direction of travel of the ele- 90 vator body and contacting at its outer end with the outer side of the rod 9. In hinging the conveyer blade or gate to the bracket 12, it will be observed that the ordinary form of stop hinge is provided, that is, the hinge 95 joint 12^a is formed on one side of the connected members, thereby permitting the ends of the bracket and the blades to abut against each other, and prevent the blade from dropping away from the guide rod 9, while at the 100 same time said blade when out of contact with said guide rod, is free to swing in the opposite direction.

14 represents an angular scraper or leveling rod, the longer arm of which is pivoted to the 105 cross frame piece 11 at one side of the center of the length of the latter. This rod has its outer termination within the channel of the elevator body, its shorter terminal arm 14^b extending transversely within said channel. 110 Journaled in boxings carried by transverse frame pieces 2^a, which connect the beams 2

- and 1, is a shaft 15 which carries on one end a belt wheel 16, to which rotary movement is adapted to be imparted by a belt from an engine or other suitable source of power.
- 5 The opposite end of the shaft 15 carries a pinion 15^a which meshes with the teeth of a gear wheel or ring 17, which surrounds and is secured to the usual form of concrete mixing drum 18.
- 10 Beyond the pinion 15^a, the shaft 15 carries a bevel pinion 19 which gears with a pinion 20 carried on a shaft 21 which is journaled transversely in boxings carried by the beams 2 and 1. The forward end of the shaft 21 15 carries a similar sprocket wheel 22 which is connected by a chain belt 22^a with the toothed ring or wheel 6 which is affixed as heretofore described, to the rear side of the circular elevator. The drum 18 which is 20 arranged, as shown, between the beams 1 and 2, is provided with the usual open or trough-like extension 23 which is below the shaft 15 and within this trough is journaled the usual drum feeding screw 24, to which 25 and the mixing blades or other devices contained in the drum 18, motion may be imparted in the usual or well known manner, by suitable gearing not herein shown.
- 25 represents an inclined chute leading to 30 the screw casing or trough, the upper and outer end of said chute extending, as shown, through the central opening of the ring-like elevator or conveyer 5. Secured to the outer face of the cross frame piece 11 is the upper 35 straight edge of a disk segment 26 which extending slightly forward, projects within and overlaps the inner portion of the rear wall 5^a of the elevator.
- In utilizing my elevating attachment, the 40 material to be mixed is deposited by dumping or shoveling into the lower portion of the rotating elevator or conveyer, with the result that the material thus received within the channel of the conveyer is engaged 45 by the gates 13 and their brackets 12, each of said gates thus forming a bucket or pocket in which the material is carried upward until the gate passes over and out of contact with the upper end of the guide rod 9, at 50 which point the gate will be permitted to swing downward on its hinge to the position indicated in the upper portion of Fig. 1 of the drawing, the gate thus depositing its load into the chute 25, from which the material will travel downward into the trough 23 and be conveyed in the usual manner to the 55 mixing drum 18. In the upward movement of the gates, they successively come into contact with the outer end portion of 60 the scraper rod 14, with the result that as said scraper rod breaks its engagement with a gate, the material contained in the bucket formed by the gate and its bracket, is substantially level, thereby insuring the carrying 65 of substantially the same amount of the

material up each of the gates and providing means whereby the operator may determine the amount of material conveyed or deposited in the mixer trough, by the number of buckets dumped therein.

70

It is sometimes customary in the operation of discharging concrete material into a mixer, to wheel the material up a comparatively steep inclined runway to a platform raised above the mixer hopper. It will be understood, however, that by the use of the herein described elevator, the material to be mixed may be fed into the lower portion of the elevator from a wheelbarrow supported at a very slight elevation from the ground 80 and such material will be automatically carried upward and dumped into the mixer chute. In order to prevent the material passing through the circular opening in the elevator or conveyer, I have provided the 85 guard or baffle plate 26 which covers the lower portion of said opening in the manner shown and described.

75

It is obvious that my improved attachment, may be employed with any of the ordinary forms of concrete mixing machines and for this reason I have not at this time shown or described in detail a particular form of mixer.

90

What I claim, is:

95

1. In a feeder for concrete mixers, the combination with a circular rotatably mounted channeled conveyer body, hinged gates at intervals in said conveyer channel, a fixed curved rod within said conveyer channel 100 terminating near the upper side thereof, and means for retaining said gates in contact with said rod until said gates have traveled past the upper termination of the rod, of a concrete mixer, a chute leading therefrom 105 into the upper portion of the conveyer, and means for rotating said conveyer.

100

2. In a feeder for concrete mixers, the combination with a circular rotatably mounted and channeled conveyer body, hinged gates at intervals in said conveyer channel, a fixed curved rod within said channel and having its upper termination in the upper portion of the conveyer, means for retaining said gates in contact with said rod until the 110 gates have passed the upper termination of the rod, a pivoted angular scraper rod adapted to project within the conveyer channel and to engage the upper or outer ends of said gates and to disengage therefrom when 115 the gates reach the upper termination of said curved rod, and means for imparting a rotary motion to the conveyer body.

110

In testimony whereof I affix my signature in presence of two witnesses.
